ADJUSTABLE MERCURY DISPENSING APPARATUS

David N. Brooks, West Peabody, Mass., assignor to Sylvania Electric Products Inc., a corporation of Delaware
Filed Nov. 18, 1965, Ser. No. 508,459
5 Claims. (Cl. 222—217)

ABSTRACT OF THE DISCLOSURE

The invention describes a dispenser for mercury, the dispenser having a slide with an opening therein; the opening being normally open to a mercury reservoir at one end and closed at the other by a slidable pin, the position of the maximum displacement of the pin being adjustable by a micrometer to regulate the volume of the opening, the slide moving the opening from the reservoir to a discharge outlet as the pin pushes the mercury out of the opening.

This invention relates to mercury dispensing apparatus useful in the manufacture of high pressure electric discharge devices containing mercury and particularly to apparatus for dispensing precise easily variable amounts of mercury.

In the manufacture of high pressure electric discharge devices, mercury dispensing apparatus is employed to introduce a given quantity of mercury into the arc tube. Older discharge devices did not require critical amounts of mercury and the equipment to dispense mercury into the device similarly did not require precision. In present types of high pressure discharge devices, however, the quantity of mercury introduced therein is extremely critical to achieve the desired light emission and color spectrum. Dispensing apparatus must therefore provide such critical doses; moreover, the doses should be easily variable to permit use of the apparatus in the manufacture of various types of discharge devices.

Conventional dispensing apparatus usually employs a slidable member having a cavity of specified size therein, and which is movable between a mercury reservoir and a discharge orifice. The cavity in the slidable member fills with mercury from the reservoir and then releases this amount of mercury into the discharge orifice when the member is moved to the discharge position. Unless used in a vacuum, the cavity in such conventional apparatus does not always fill completely thereby causing error in the amount of mercury which is dispensed. Furthermore, dispensed amounts can be varied only by replacing the slidable member with another containing a different cavity size. Such interchanging of parts is most inconvenient and does not lend itself to automated equipment.

In accordance with the present invention, the dispensing apparatus comprises a vertically slidable member with a horizontal cylindrical bore therein and a metering pin adjustably disposed in the bore. When the slidable member is in the raised position, mercury flows from a reservoir into the cylindrical bore in an amount precisely determined by the adjustment of the metering pin. As the member is lowered, the metering pin is cammed or otherwise urged further into the bore causing the mercury to be discharged into a suitable orifice and thence to the electric discharge device being filled.

The invention will be more fully understood from the following detailed description, taken in conjunction with the accompanying drawing, in which:

FIG. 1 is a sectional elevation view of apparatus according to the invention; and

FIG. 2 is a top view of the apparatus of FIG. 1.

Referring to the drawing, there is shown an annular

2

housing 10 having a partially cylindrical member 12 disposed therein, and a vertically slidable rectangular member 14 located in a slot 16 provided in member 12. A cylindrical hole 18 in member 12 provides the mercury reservoir and has an opening 20 in the lower end of the reservoir for supplying mercury to the dispensing slide, as will be further explained hereinafter. The lower portion of member 12 is semi-cylindrical and has a groove 22 cut in this lower portion which communicates with a discharge orifice 24 in the bottom portion of housing 10. Member 14 has a horizontal bore 26 formed in the lower end thereof, for example, in a bushing 60 set in the lower end thereof as shown in FIG. 1, with a metering pin 28 slidably mounted in bore 26 and having a magnetic head 30 attached to the end of pin 28 outside the bore. Member 14 is slidably retained in slot 16 by a rectangular element 32 held in position by suitable fasteners such as set screws 34 and 36 threaded into holes provided in the wall of housing 10.

10 A micrometer mechanism 38 is attached to housing 10 with the micrometer spindle 40 being attached to a stop plate 42 containing a magnet 44 to provide adjustment of the stop plate. Vertical movement of slide 14 is provided by a solenoid 46 supported above housing 10 by 15 an annular structure 56 and cooperating with a magnetizable head 48 connected to the slide via a rod 50. A damping vane 52 is also connected to head 48 via a rod 54.

20 In operation, the size of the bore is adjusted by varying the position of pin 28 in the bore by means of micrometer 38, and discharge orifice 24 is connected to an electric discharge device to be filled. Solenoid 46 is energized from a suitable electrical source (not shown) to urge head 48, and hence slide 14, to the raised position with bore 26 in alignment with opening 20, causing mercury to flow from the reservoir into the bore in an amount determined by the position of pin 28. Solenoid 46 is now de-energized, allowing slide 14 to fall by gravity. When bore 26 reaches slot 22, head 30 is engaged by a camming block 58 in the bottom of housing 10 which urges pin 28 into the bore causing the measured amount of mercury therein to flow into orifice 24 and thence to the device being fabricated. Although not always necessary, it has been found desirable to retard the rate of descent of slide 14, for example, via the damping action of vane 52 in the mercury bath. In this way, the mercury is dispensed at a slower rate, minimizing the tendency of mercury to splatter into droplets. The solenoid is again energized to raise slide 14, and the hydrostatic force of 25 the mercury, together with the magnetic attraction of head 30 by magnet 44, moves pin 28 out of bore 26 to a position determined by the adjustment of stop plate 42. Bore 26 fills with the measured amount of mercury which is then dispensed in the manner described hereinbefore. It 30 should be noted that the space within the bore, when conveying mercury, is completely filled by the mercury and the pin, since the pin pushes the mercury out; thus little air remains therein to interfere with complete filling of the bore by the mercury.

35 Apparatus according to the invention has been constructed of stainless steel and has been successfully operated to dispense mercury in precise quantities up to approximately 125 milligrams. Various modifications and 40 constructional variations will occur to those versed in the art, and it is not intended to limit the true scope of the invention by what has been particularly shown and described, except as indicated in the appended claims.

45 I claim:

50 1. Mercury dispensing apparatus comprising, a mercury containing reservoir, a discharge orifice, a slidable member containing an opening therein and a slidable pin 55 adjustably disposed in said opening at one end to close

the same and fix the amount of mercury which can be held in the opening, means for adjusting the position of said pin in said opening at a first position of said slideable member, and means for moving said slideable member between said first position to allow mercury in said reservoir to enter said opening and a second position to cause said pin to move into said opening to push the mercury therein into said discharge orifice.

2. Mercury dispensing apparatus comprising, a mercury containing reservoir, a discharge orifice, a slideable member containing an opening therein and a slideable pin adjustably disposed in said opening at one end to close the same and fix the amount of mercury which can be held in the opening, means for adjusting the position of said pin in said opening at a first position of said slideable member, means for moving said slideable member between said first position and a second position, means operative when said slideable member is in its first position to allow mercury to flow from said reservoir into said opening, and means operative when said slideable member

moves to its second position to urge said pin into said opening to thereby push the mercury therein into said discharge orifice.

3. Apparatus according to claim 2 in which said last mentioned means includes a camming surface to urge said pin into said opening.

4. Apparatus according to claim 2 in which said second mentioned means includes a solenoid operatively associated with a magnetizable core.

5. Apparatus according to claim 2 in which said first mentioned means includes a micrometer screw.
